UNITED STATES PATENT OFFICE.

ASBURY F. MOOD, OF CLAREMORE, OKLAHOMA.

WELL-BUCKET.

1,267,438.

Specification of Letters Patent. Patented May 28, 1918.

Application filed August 25, 1916. Serial No. 116,894.

To all whom it may concern:

Be it known that I, ASBURY F. Mood, a citizen of the United States, residing at Claremore, in the county of Rogers and State of Oklahoma, have invented new and useful Improvements in Well-Buckets, of which the following is a specification.

This invention relates to improvements in well buckets, and is primarily designed for use in connection with drilled or bored wells.

The primary object of the invention is the provision of a bucket of the above stated character which shall be simple in construction, durable in use, and comparatively inexpensive to manufacture, and which will allow of the free inflow of water into the bucket, and further to warrant the complete drainage of such water therefrom.

A still further object of the invention is the provision of a valve casing formed with a series of concentrically disposed openings, a valve mounted therein, operating means for said valve, and suspending means having connection with the valve operating means for retaining the valve within the casing at a point above the openings thereof, for permitting of the water remaining in the bucket, or which may have collected in the same due to rains, to drain therefrom, and thus leave the bucket in a dry condition, and warrant of a free circulation of air through the bucket at all times, when the bucket is not in use.

With the above and other objects in view, the invention consists in the novel features, details of construction, and combination of parts which will hereinafter be more fully set forth, illustrated in the accompanying drawing, and pointed out in the appended claims.

Figure 1 is a view of a well bucket shown in vertical section, with the parts operatively arranged and connected therewith, showing the valve in closed position;

Fig. 2 is a similar view to Fig. 1, illustrating the valve in an open position; and

Fig. 3 is a view of the valve removed from the casing with its operating rod connected thereto.

Referring more particularly to the accompanying drawings, in which like characters of reference refer to corresponding parts, 5 denotes a well bucket, which is preferably constructed of galvanized sheet metal, and having secured therein a plate 6, said plate 6 being fitted tightly against the inner walls

of the bucket above the bottom edge thereof, and said plate is formed with a centrally located opening 7. Disposed across the upper open end of the bucket 5, is a cross bar 8, 60 having its angular ends 9 fastened to the interior surface of the bucket at diametrically opposite points, through the medium of fasteners 10. These fasteners also connect with the bucket a bail 11. Reposed upon the plate 6, and over the opening 7 formed therein, is a hollow cylindrical valve casing 12 having operatively mounted therein a valve 13. The said valve 13 has connected to the bottom surface thereof a gasket 14, while fastened 70 in the upper face thereof is a screw eye 15. The valve operating rod 16 is formed with a lower end 17 adapted to engage in the eye 15 for operatively connecting the rod with the valve, and the upper end of the rod is 75 provided with a ring 18 for the insertion of the finger therein, in order to exert a pull on the rod 16 to operate the valve 13, when the occasion so demands. The rod 16 is operatively mounted in the slot 19 of the cross bar 80 8, and is retained in the slot through the medium of a keeper 20. A portion of the rod 16 is offset laterally as at 21 to provide a substantially V-shaped stop 22, and the purpose of which, when an upward pull is exerted upon the valve rod 16, is to engage with the cross bar 8, and limit the upward stroke of the valve 13 within its casing 12, and thereby preventing the removal or displacement of the valve from its casing. 90

It is the purpose of this invention to provide a novel form of well bucket, whereby when the bucket is not in use, or the water is being emptied therefrom, such water will be permitted to drain out through the opening in 95 the plate, thus leaving the bucket in a dry condition, and also permitting the free circulation of air through the bucket at all times, and retaining the same in a dry, clean and sanitary condition. To this end, the 100 valve casing or tube 12 is provided with a series of slots or openings 23, and these slots or openings extend for a portion of the length of the casing or tube 12, and open out through the bottom edge of the tube or casing 12, and allow the free inflow of water into the bucket, when the same is being lowered into the well. During such operation of the bucket, the valve 13 is elevated within the casing or tubing 12 by the force of 105 the water passing in through the opening 7 of the plate 6. The said slots or openings 23,

of course, as will be understood, further permit the outflow of water when the valve is operated through the medium of its rod 16 in a raised, position above the openings 23, 5 causing the emptying of the bucket.

Swingingly mounted on the rivet pin 24, which passes through the U-shaped loop 25, of the bail 11, is a keeper 26, having a lower hooked end 27, and the purpose of this 10 keeper is to engage or hook in the finger opening 18 of the valve operating rod 16 for retaining the valve in a hoisted position, or in a position above the openings or slots 23, whereby when the bucket is not in 15 use, will permit of the free circulation of air through the bucket at all times, and cause the bucket to retain a dry and sanitary condition.

In the operation of this invention, the 20 valve rod 16 is released from the keeper 26, allowing the valve to repose upon the plate 6 and over the opening 7 therein, the bucket then being lowered into the well, and as the same strikes water, the pressure thereof from 25 below, together with the weight of the bucket forces the valve to rise in the valve casing or tubing 12, thus allowing of a free inflow of water in the bucket through the respective openings 7 and 23, until the bucket 30 is filled with water, after which the water in the bucket will cause the valve to be moved in engagement with the plate 6 and over the opening 7 therein, thus preventing the escape of water from the bucket while the 35 bucket is being raised from the well. When the bucket is taken from the well, the same is placed in the receptacle to be filled with the water, and the valve is thence raised by inserting the finger into the opening 18 of the 40 valve rod, and lifting the valve to release the water from the bucket, after which the opening 18 in the valve rod is placed upon the hooked end 27 of the keeper 26 for retaining the valve in non-obstructing relation with 45 respect to the opening 7 of the plate 6, and the openings 23 of the valve tube or casing 12, thereby allowing of a free circulation of the air through the bucket at all times.

From the foregoing description, taken in 50 connection with the accompanying drawing,

the advantages of construction and of the method of operation will be readily apparent to those skilled in the art to which the invention relates, and while I have described the principles of operation of the invention, 55 together with the device which I now consider to be the best embodiment thereof, I desire to have it understood that the device shown is merely illustrative, and that such modifications may be made when desired as 60 are within the scope of the claims appended thereto.

I claim:

1. A well bucket having a closed bottom formed with an opening, a tubing supported 65 upon the bottom of the bucket, and provided with a pair of diametrically arranged openings communicating with the opening of the bottom, a valve operatively mounted in said tubing, a bail, and a hook supported 70 by the bail of the bucket for holding the valve in a raised position with said casing.

2. A well bucket having a closed bottom, formed with an opening, a bail for said bucket, a casing supported upon the closed 75 bottom of the bucket and over the opening therein, and having a series of openings, a valve operatively mounted in said casing, operating means for said valve, and a hook suspended from the bail of the bucket 80 engaging with the valve operating means for suspending the same in non-obstructing relation with respect to the opening of the bottom and the openings of said casing.

3. A well bucket having a closed bottom 85 formed with an opening, a casing supported upon the bottom and over said opening, a valve slidably mounted in said casing, a rod for operating said valve, said rod being bent 90 to provide a laterally extending stop for limiting the upward stroke of the valve substantially as and for the purpose specified.

In testimony whereof I affix my signature in presence of two witnesses.

ASBURY F. MOOD.
